Primary Examiner — Nicole C Shiflet*Assistant Examiner* — Danielle Nichole Bowly(74) *Attorney, Agent, or Firm* — Carlson, Gaskey & Olds, P.C.(57) **CLAIM**

I claim the ornamental design for a pad for a 3D printer pen, as shown and described.

DESCRIPTION

FIG. 1 is a perspective view of a pad for a 3D printer pen. FIG. 2 is a front view of a front side of the pad for a 3D printer pen.

FIG. 3 is a back view of a back side of the pad for a 3D printer pen.

FIG. 4 is a first side view a first side of the pad for a 3D printer pen.

FIG. 5 is a second view of a second side of the pad for a 3D printer pen.

FIG. 6 is a first end view of a first end of the pad for a 3D printer pen.

FIG. 7 is a second end view of a second end of the pad for a 3D printer pen.

FIG. 8 is a cross-sectional view taken along line 8-8 in FIG. 2 of the pad for a 3D printer pen; and, FIG. 9 is cross-sectional view taken along the line 9-9 in FIG. 3 of the pad for a 3D printer pen.

The broken lines represent portions of the pad for a 3D printer pen that form no part of the claimed design.

1 Claim, 5 Drawing Sheets(56)
